CLAIM

I claim the ornamental design for a decorative liquid metal degassing impeller, as shown and described.

DESCRIPTION

FIG. 1, which is a front isometric view of a decorative liquid metal degassing impeller as claimed;

FIG. 2, which is a front top view of a decorative liquid metal degassing impeller as claimed;

FIG. 3, which is a back isometric view of a decorative liquid metal degassing impeller as claimed;

FIG. 4, which is a back top view of a decorative liquid metal degassing impeller as claimed;

FIG. 5, which is a side elevation view of a decorative liquid metal degassing impeller as claimed; and,

FIG. 6, which is a side elevation view of a decorative liquid metal degassing impeller as claimed and which is rotated by 22.5 degrees from the view presented in FIG. 5.
